(57) **CLAIM**

The ornamental design for a display hook, as shown and described.

DESCRIPTION

FIG. 1 is a front perspective view of a display hook showing our new design;

FIG. 2 is a top plan view thereof;

FIG. 3 is a side elevational view of the left-hand side thereof, the right-hand side view being a mirror image of FIG. 3;

FIG. 4 is a rear elevation view thereof; and

FIG. 5 is a front elevational view thereof; and,

FIG. 6 is a bottom plan view of our new design for a display hook.
